UNITED STATES PATENT OFFICE.

FRED F. REISNER, OF ST. LOUIS, MISSOURI, ASSIGNOR TO RICHARD L. BARRINGTON, OF ST. LOUIS, MISSOURI.

TOY.

SPECIFICATION forming part of Letters Patent No. 784,888, dated March 14, 1905.

Application filed February 27, 1904. Serial No. 195,639.

To all whom it may concern:

Be it known that I, FRED F. REISNER, a citizen of the United States, and a resident of the city of St. Louis and State of Missouri, have 5 invented a new and useful Improvement in Toys, of which the following is a specification.

My invention relates to toys, and has for its principal objects to provide a toy consisting of more than one part so arranged that it can be assembled only in the proper way, to provide a toy of more than one part, each having on its exterior a portion of a representation of some object and so arranged that 10 it can only be assembled in such manner as to complete the representation, to provide a nested toy having the successive figures arranged so that they can be assembled only in the proper relation to each other, and other 15 objects hereinafter more fully appearing.

My invention consists in the parts and in the arrangements and combinations of parts hereinafter described and claimed.

Figure 1 is a side view of my improved toy 25 assembled. Fig. 2 is a front view showing the upper part of the outside figure raised and disclosing the next inner figure. Fig. 3 is a vertical central sectional view through the assembled toy. Fig. 4 is a plan view of the 30 bottom part of one of the figures. Fig. 5 is a vertical central sectional view through the assembled toy made of sheet metal. Fig. 6 is a plan view of the bottom part of one of the sheet-metal figures.

My improved toy consists of a series of 35 nested figures *a b c d*, four being shown in the toy shown to illustrate the invention. Each figure except the inmost one in the form shown in Fig. 3 is made in two parts.

The bottom part 1 of each figure has a rabbeted edge 2. The rabbet extends almost entirely around the upper edge. A small projection 3 is, however, left for a purpose hereinafter appearing. In the form shown in 40 Figs. 3 and 4 this projection is integral; but obviously it may be a pin inserted in the edge after the latter has been rabbeted entirely around it. The upper part 4 of each figure has its lower edge provided with a comple-

mentary rabbet and has a recess to register 50 with the projection. Obviously the parts can be assembled in but one way.

The parts may be given any desired shape. In the toy illustrated the exterior has been provided with a superficial representation of 55 a woman, a portion of the representation being on the lower part 1 and a portion upon the upper part 4. If it were not for the projection 3 and recess in the lower and upper parts, respectively, the figures might be assembled so that the portion of the representation would bear any relation to each other than the right one. The projection, however, necessitates the assemblage of the parts in such manner that the portions of the representation will be in proper positions with respect to each other. The representation upon the exterior of the figure may be either superficial, bas-relief, intaglio, &c. The representation may be of any desired object or a 60 plurality of objects.

In the bottom part 1 of the outermost figure an upwardly-extending pin 5 is secured outside of the center of the figure. The several inner figures are provided with holes registering with said pin. Thus it is impossible to nest the several figures in more than one way. The representations on the exteriors of the figures are so located with respect to the position of the pin and the holes registering 75 therewith that all the nested figures will face the same way. Without this arrangement the several figures might face as many ways as there are figures.

In Figs. 5 and 6 a sheet-metal form of the 80 toy has been illustrated. In general arrangement it is the same as the wooden toy illustrated in Figs. 3 and 4. The upper rabbeted edge 2' of the lower part of each figure is produced by offsetting the upper margins. At 85 one point there is an indentation in this offset margin, producing a projection 3' to control the assembling of the parts. The top part of each figure fits down into the rabbet and is cut away at the part that registers with 90 the projection 3'. The nesting of the toys is controlled by projections 6', extending upwardly from the bottom part of each succes-

sive figure. In making the projections in sheet metal a recess is incidentally produced on the opposite side. The projections are so proportioned in the successive figures that the 5 recess in the bottom of one will just fit over the projection in the succeeding outer figure. The projections are positioned outside the center of the figures, so as to prevent the nesting of the figures in more than one position with 10 respect to each other.

The toy is used for the amusement of children in much the same way as are ordinary dolls. It has the additional advantage of providing amusement in the separation and assemblage of the parts of the individual figures and the separation and nesting of the several figures.

Obviously my device admits of modification within the scope of my invention, and therefore I do not wish to be limited to the specific construction shown and described.

What I claim as my invention, and desire to secure by Letters Patent, is—

1. A toy comprising a plurality of nested 25 figures, each provided with a representation of an object or objects on its exterior, and certain of said figures comprising separable parts, a portion of the representation being upon each part, a projection upon one of the separable parts of each figure and a recess in the other part arranged to register with said projection whereby said parts can be assembled only with the portions of the representation in proper position with respect to each other.

35 2. A toy comprising a plurality of nested figures each provided with a representation of an object or objects on its exterior, the in-

ner figures being entirely surrounded by the outer figures, and means to compel the nesting of said figures with all the figures facing 40 the same direction.

3. A toy comprising a plurality of nested figures, each provided with a representation of an object or objects on its exterior, and certain of said figures comprising separable parts, 45 a portion of the representation being upon each part and means to compel assembling the separable parts of each figure in a predetermined position with respect to each other.

4. A toy comprising a plurality of nested 50 figures, each provided with a representation of an object or objects on its exterior, the inner figures being entirely surrounded by the outer figures, and corresponding projections and recesses upon said figures arranged to 55 compel nesting said figures with all the figures facing in the same direction.

5. A toy comprising a plurality of nested figures, certain of said figures consisting of separable parts, and each of said figures having 60 a representation upon its exterior and means to compel assembling said separable parts with the portions of said representation in proper position with respect to each other, and means to compel the nesting of said figures with all 65 the figures facing the same way.

In testimony whereof I have signed my name to this specification, in the presence of two subscribing witnesses, at St. Louis, Missouri, this 24th day of February, 1904.

FRED F. REISNER.
